(57) **CLAIM**

The ornamental design for a surgical fastener, as shown and described.

DESCRIPTION

FIG. 1 is a perspective view of a surgical fastener.

FIG. 2 is a front elevation view of the surgical fastener of FIG. 1.

FIG. 3 is a rear elevation view of the surgical fastener of FIG. 1.

FIG. 4 is a top plan view of the surgical fastener of FIG. 1.

FIG. 5 is a bottom plan view of the surgical fastener of FIG. 1.

FIG. 6 is a left elevation view of the surgical fastener of FIG. 1.

FIG. 7 is a right elevation view of the surgical fastener of FIG. 1.

FIG. 8 is a perspective view of a surgical fastener.

FIG. 9 is a front elevation view of the surgical fastener of FIG. 8.

FIG. 10 is a rear elevation view of the surgical fastener of FIG. 8.

FIG. 11 is a top plan view of the surgical fastener of FIG. 8.

FIG. 12 is a bottom plan view of the surgical fastener of FIG. 8.

FIG. 13 is a left elevation view of the surgical fastener of FIG. 8; and,

FIG. 14 is a right elevation view of the surgical fastener of FIG. 8.

In all figures, broken lines illustrate environmental structures and form no part of the claimed design.
